UNITED STATES PATENT OFFICE.

JOSEPH BUTTON LINDSEY, OF LOCKWOOD, MISSOURI.

CALENDAR-CHART.

No. 849,251.

Specification of Letters Patent.

Patented April 2, 1907.

Application filed March 15, 1906. Serial No. 306,156.

To all whom it may concern:

Be it known that I, JOSEPH BUTTON LINDSEY, a citizen of the United States, and a resident of Lockwood, in the county of Dade and State of Missouri, have invented a new and Improved Calendar-Chart, of which the following is a full, clear, and exact description.

The purpose of the invention is to provide a calendar device or chart so arranged that the number of days from a given date to any other date in the past or in the future and maturity dates can be readily and expeditiously found and accurately read in days.

The invention consists in the novel construction and combination of the several parts, as will be hereinafter fully set forth, and pointed out in the claims.

Reference is to be had to the accompanying drawings, forming a part of this specification, in which similar characters of reference indicate corresponding parts in all the figures.

Figure 1 is a plan view of the improved chart device, and Fig. 2 is a section through the same.

In carrying out the invention twelve charts or leaves A are provided, one for each month of the year, the chart for the current month having the name of that month at the top of the chart in the extreme outer right-hand and left-hand columns, the names of the other months of the year being in parallel columns, varying in their arrangement relatively to the outer or initial columns according to the names of the months appearing in said initial columns.

The chart illustrated and that which will be described is for the month of October. The chart is placed upon and is secured to a board B, the attachment being made in such manner that the charts may be removed when desired.

At the central portion of the chart A a space a is provided, which may be termed a "working" space, and said space extends from the top to the bottom of the chart. In the upper portion of said space figures are printed at equal distances apart in a longitudinal column, which figures represent the days of the month, and said figures read from "31" at the top consecutively to "1" at the bottom, included. The last figure in said column is at about the central portion of the said space a. An aperture a' is produced in the space a just below each of the aforesaid figures designating days, and these apertures a' register with apertures a², made in the

board B. In connection with the said row of figures designating the days of the month what I term a "computing-strip" C is employed. The strip C is of sufficient length to extend from the lowermost aperture a' substantially to the lower end of the board and is provided at its upper end with a pin b, extending beyond its rear face, which pin is adapted to enter any of the apertures a' in the chart and corresponding apertures in the board B. This computing-strip C is preferably made of thin metal, so that it will lie flat on the chart, and upon its outer face a longitudinal column of figures is produced, also representing the days of the month, and these figures, which are spaced apart correspondingly to the figures in the space a, read just the reverse, commencing with "1" at the top and ending with "31" at the bottom.

With reference to the arrangement of the matter upon the body of the chart A, the said chart is shown divided about centrally and transversely by a dotted line X, which line, together with the central space a, divides the matter upon the outer face of the chart into four panels of practically equal size—namely, an upper left-hand panel D, a lower right-hand panel D', a lower left-hand panel D², and an upper right-hand panel D³. The data upon all of the said panels are read relatively to the days of the month in the space a and on the computing-strip C, as will be hereinafter described. The panels D and D² are utilized when time is to be calculated intervening between a present date and a past date, while the panels D' and D³ are used where information is desired as to time intervening between a present date and a future date. Both panels D and D² at the left of the chart are headed backward and the panels D' and D³ to the right of the chart are headed forward.

With reference to the panel D at the upper left-hand portion of the chart, the outer or initial column d contains the abbreviation or name of a current month placed above figures representing the days thereof and reading consecutively from "30" at the top to "1" at the bottom, which are the days of the month of October less one, there being thirty-one days in October. In connection with this column parallel columns d' are employed, reading "Nov." "Dec." "Jan." "Feb." "Mar." "Apr." "May" "Jun." "Jul." "Aug." "Sep." September is the innermost column of the columns of months, and

the designations of the months in the columns d and d' are in transverse alinement with the figures in the space a designating the days of the month. Beneath the name of each month in the columns d' is printed in figures the number of days reading backward from an initial day in the space a to the same day in the months contained in the said columns d' and reading transversely with the said initial day in the space a . In this instance the figures for the panels D' and D^3 are produced by calculating the number of days from the initial day and month, October 31, to November 1, and placing the result in the right-hand November column one line below that occupied by the figure "31." The figure "2," or the difference from October 30 to November 1, is next placed in the November line. The figure "3," the time from October 29 to November 1, is next in line, and thus the figures are produced for the said column until the time from each day in October to the first day in November is shown, the last figure being "31," which represents the days from October 1 to November 1. The next figures indicate the time from October 1 to November 2, which is thirty-two days, to the third of November, thirty-three days, and in this manner all the days of November are represented in the column, which now shows as many lines of figures as there are days in October and November less one day, making sixty days in all. The figures in the next column, which in this instance are those for December, are produced in a similar manner. The figure "31," with which the December column begins, represents the days from October 30 to December 1. "32," the next figure in line, represents the days from October 30 to December 2, and in this manner the figures for this column are produced until "61" is reached, and all of the days of the months from October 30 to December 31 are shown. The next figures in the column shows the time from October 30 to December 2 and the next to December 3, and so the remaining days are scored, ending at "91." The figures in the panels D and D' are obtained in a similar manner, the number of days that intervene between each day in the initial month to the first of the months column and then to all the days of the month are shown as before. In this instance one day less than the whole number of days is counted in consequence of the custom in some communities to reckon the beginning and ending days on one day, while in other communities they are counted as two days. I contemplate incorporating the figures in my chart in the order adapted to different communities. Further, above each column of months d' a number is printed designating the calendar number of the month expressed in the column beneath, the sequence being backward relative to the initial month ex-

pressed in the initial column d . As, for example, October being the initial or current month, September would be designated as "1," August as "2," &c., since the reading obtained from this panel, as stated, is backward.

The arrangement of the data in the panel D^2 just beneath the said panel D is identical with the arrangement of the data in the panel D , except for the numbers appearing beneath the names of the months in the columns, wherein the initial column, or that containing the name or abbreviation of the current month, is designated as d^2 , the other parallel columns being designated as d^3 . In the arrangement of the panel D^2 , which, as stated, is utilized for working out the number of days from a present date to a past date, the first day is expressed by the figure "1" beneath the last word or abbreviation "Sep." in the September column d^3 , which is immediately to the left of the central space a , and from this point reading upward in each column d^3 and in the initial column d^2 the figures chronologically increase until under the word or abbreviation "Oct." at the top of the initial column d^2 the number "365" appears, expressing the total number of days in a year.

I desire it to be understood that in each and all of the panels on the chart the abbreviations of the names of the months designating the columns are repeated as many times in the columns as may be required.

In the panel D' the outer column d^4 is the initial column, containing the abbreviation "Oct." and having produced after each abbreviation a figure representing a day of the month, and contrary to the corresponding arrangement in the panel D the figures in the column d^4 of the panel D' read from "1" at the top consecutively to the bottom. The parallel month-columns d^5 are also arranged in reverse order, since the column for November is the innermost column and the other month-columns read in regular order to the outer right-hand or initial column d^4 , the next month-column thereto being the September column. The figures below the names of each month in each column are obtained in the same manner as the figures appearing upon the panel D , but read in reverse order—that is, from the top of the column downward—and the chronological sequence is in the direct or calendar order of months.

At the right and left hand sides of the space a a series of figures is produced, one above each vertical column, and these figures are to indicate the calendar months from any given day in the initial month of October to a like date in any other month. To illustrate, to find the number of calendar months from October 28 to May 28 above the May column the figure "5" is written, show-

ing it to be five calendar months, or from October 28 to March 28 forward above the March column the figure "5" is to indicate the calendar months between these two latter dates; but I do not specifically claim the calculations of the calendar months, as the calculations are obtained by days.

With reference to the upper right-hand panel D⁸ in the October chart the month-column next to the space *a* is November instead of September, since this panel is used in calculating time intervening between a present and a future date, and the month-columns *d*⁸ read in calendar order to the right-hand initial October column *d*⁷. The numbers beneath each abbreviation of the name of a month in each column of the said panel read chronologically from "1" to "365" from the tops of the columns downward, "1" being at the head of the November column and "365" at the foot of the initial or October column. It may be here set forth that the initial column *d* in the panel D and the corresponding initial column *d*⁴ in the panel D' may be termed "columns of odd days," since they show only the time from dates to dates in the initial months and never contain the full number of days of the month.

In the explanation of the operation let it be supposed that the present date is October 15. The pin of the computing-strip C is placed in the aperture just below "15" in the days-column in the space *a*, the figure "15" appearing above the strip, as illustrated. Now to find how many days measure back to January 10, begin with the figure "10" on the computing-strip and follow to the left along the transverse line of months and figures registering with said figure "10" until the January column is reached. Now look immediately below the word "January" on the said transverse line and the figures "278" will be read, thus showing that it is two hundred and seventy-eight days back to January 10.

To obtain the time from the 12th day of March to the 15th day of October, find "12" on the computing-strip, following to the left alining row of months and numbers until the March column is reached, and immediately below the word "March" on the said transverse line the figures "217" will be seen, thus showing that it is two hundred and seventeen days from the 12th day of March to the 15th day of October. Now, for example, find the time back to November 25 from October 15. Begin at "25" on the computing-strip and trace transversely to the left until the November column is reached, and immediately below the word "November" in the alining row of months "324" is seen, being the number of days back from October 15 to November 25. In order to find the days to a given future time, the operation is the

same, except that the alining rows of months and figures are traced to the right.

If it is desired to know how far it is to October 31 from the present 15th of October, begin at "31" on the computing-strip C and trace transversely to the right until the October column is reached, and the figures "16" immediately below the "October" in alinement is the answer in days, or, following the line of months and figures to the left registering with the figure "31" on the computing-strip C until the October column is reached, I find immediately below the "October" in alinement the figure "349," which is the number of days from October 15 back to October 31.

In the column of figures upon the computing-strip C over the figure "28" I contemplate printing the warning "February has only 28 days," and over the figure "30" that April, June, September, and November have thirty days only. The figures indicating the number of days on the twelve leaves of this chart occupying in each instance nearly the same place, their location is soon learned and readily found. For example, I wish to find the maturity date of a note given October 15 for thirty days. By looking down the first line of months to the right of the working column I discover the figure "30" under the word "November" and in alinement to the left on strip C is the figure "14," and I thus learn that the note matures November the 14th, or, if three days of grace are to be added, then on the 17th, or, for a similar example, a note dated October 15, to run one hundred and twenty-five days, in the February column I discover "125," above which is the word "February" and in alinement on the strip C is the figure "17," and I perceive the note matures on the 17th of February.

To further illustrate, let it be supposed that the present date is October 30. The pin of the computing-strip C is placed in the aperture just below "30" in the days column in the space *a*. Now to find how many days it is back to October 1, begin with the figure "1" on the computing-strip C and follow to the left along the transverse line of months and figures registering with said figure "1" until "October" is reached, and beneath the word "October" in said column is the figure "29," being the number of days from October 30 back to October 1, or, for another example, beginning with the figure "30" on the strip C and going to the right along the transverse line of months and figures until "October" is reached, and beneath the word "October" in said column is the figure "365," showing it to be one year from October 30 to the next 30th day of October; or to follow in the same manner to the left from "30" on the strip C until "October" is

reached, and beneath the word "October" is the figure "365," showing it to be one year back to the last past October 30, or, beginning at "31" on the strip C and following in the same manner along the transverse line of months and figures to the right until "October" is reached, and beneath the word "October" in said column is the figure "1," showing it to be one day from October 30 to October 31. For example, I wish to find the maturity date of a note of the present date given for thirty days. I discover "30" in the manner and space as in the previous illustration, but to the right, upon the computing-strip C. I also perceive that with the change of date from October 15 to the present supposed date October 30, the figure upon the said strip has also correspondingly changed and the figure now in line is "29," and I thus perceive that a note dated October 30, for thirty days will mature November 29. I also find "90" under "January" in the January column, and to the left I find "28" upon the strip C, and thus I find that a note of present date for ninety days would be due January 28, or, if three days' grace are to be added, then on January 31.

It may be here remarked that in many interest-calculating books employed in commercial houses the interest is reckoned by days and months of thirty days each, while in other interest-books much used in the commercial world interest is calculated by days only. With a view to making the calendar-chart useful for both systems I have given the time in days only; but the days may be reduced to months and days according to any system that may be desired and the answers so written. I contemplate the adaptation of the chart to both methods for indicating totals.

It will be observed that in the columns of months to the right of the working space *a* the name of that month is repeated in this column as many times as there are days in the initial month, which in this instance is October, less one day, together with the total number of days in the succeeding month of November, making sixty repetitions of the word "November" in this column, or the thirty-one days of October less one day, making thirty to add to the twenty-eight days in February, making fifty-eight repetitions of the word "February" in the February column.

Having thus described my invention, I claim as new and desire to secure by Letters Patent—

1. A calendar - chart having a series of panels arranged one above the other, two to the right and two to the left and a space dividing the right-hand from the left-hand panels the said space having a longitudinal row of figures representing days of a month produced thereon, each panel consisting of

longitudinal and parallel columns of names of the months, the outer columns expressing the name of the current month, and chronologically-arranged figures appearing beneath the names of the months, each panel having an independent arrangement of figures, and a computing-strip adapted for attachment to the chart at any point in the row of figures in the said separating-space, the said strip having thereon a row of figures representing the days of a month but arranged in reverse order to the row of corresponding figures in the said separating-space, the figures in said separating-space and on said strip being read in connection with the names of the months and the figures on the columns of said panels.

2. A calendar - chart having a series of panels arranged one above the other, two to the right and two to the left, the panels to the right and to the left being divided by a separating-space, in which space at its upper portion a row of figures is produced representing the days of the month and reading downward from the greatest to the smallest number, each of the said panels comprising parallel columns and each column consisting of a series of the name of a month in the year, the outermost column of each panel bearing the name of the current month, and figures which appear below each name in each column, said figures being chronologically arranged, the figures in the right-hand panel reading in one direction and the figures in the left-hand panel reading in an opposite direction, each column being headed by a numeral representing the calendar-number of the month represented by the column, and a computing-strip having a row of figures thereon representing the days of a month, the said figures reading from top to bottom of the strip or in reverse order to the reading of the figures in the said separating-space, and means for adjustably securing the said separating-strip at a point below any one of the figures produced on the said separating-space.

3. A calendar - chart having a series of panels produced thereon, four in number and arranged one above the other, two to the right and two to the left, the right and left hand panels being provided with a longitudinal separating-space in which space at its upper portion a row of figures is produced representing the days of the month and reading downward from the greater number to the lesser number, each of said panels comprising a series of parallel columns, each column bearing the repetition of the name of a given month, the outermost column of each panel bearing the repetition of the name of the current month, figures at the top of said columns designating the calendar-number of the several months in the columns, numbers chronologically arranged and representing days of the year, produced one number beneath each repeated name in each column of

the panels, the arrangement of the names of the months in the left-hand panels being the same, and the arrangement of the names of the months in the right-hand panels being 5 in corresponding order, the numbers below the names of the columns being chronologically arranged in each panel from 1 to 365, the reading of the numbers in the upper left-hand panel commencing with 1 at the bottom of the outer column, the arrangement of 10 the numbers in the lower right-hand panel commencing with 1 at the top of the outer column, the arrangement of the numbers on the lower left-hand panel commencing with 1 15 at the bottom of the inner column and the arrangement of the numbers in the upper

right-hand panel commencing with 1 at the top of the inner column, a computing-strip having a row of figures thereon representing the days of the month and reading in reverse order to the order of the column of figures in the separating-space, and means for removably securing said computing-strip at points on the said chart below any one of the figures in the said separating-space, as described. 20 25

In testimony whereof I have signed my name to this specification in the presence of two subscribing witnesses.
